(57) **CLAIM**

The ornamental design for a shaver, as shown and described above.

DESCRIPTION

The patent or application file contains at least one drawing executed in color. Copies of this patent or patent application publication with color drawings will be provided by the Office upon request and payment of the necessary fee.

FIG. 1 is a perspective view of a shaver;

FIG. 2 is a front view thereof;

FIG. 3 is a right side view thereof;

FIG. 4 is a rear view thereof;

FIG. 5 is a left side view thereof;

FIG. 6 is a top plan view thereof;

FIG. 7 is a bottom view thereof.

FIG. 8 is a perspective view of a shaver;

FIG. 9 is a front view thereof;

FIG. 10 is a right side view thereof;

FIG. 11 is a rear view thereof;

FIG. 12 is a left side view thereof;

FIG. 13 is a top plan view thereof;

FIG. 14 is a bottom view thereof.

FIG. 15 is a perspective view of a shaver;

FIG. 16 is a front view thereof;

FIG. 17 is a right side view thereof;

FIG. 18 is a rear view thereof;

FIG. 19 is a left side view thereof; FIG. 20 is a top plan view thereof; and,

FIG. 21 is a bottom view thereof.

The broken lines shown in the drawings illustrate portions of the article and form no part of the claimed design.
